DESIGN FOR A SHOE TREE

James B. Mutch, Rochester, N. Y., assignor to
Schelter Last Co., Inc., Rochester, N. Y., a cor-
poration of New York

Application July 4, 1942, Serial No. 107,431

Term of patent 14 years

To all whom it may concern:

Be it known that I, James B. Mutch, a citizen of the United States, residing at Rochester, in the county of Monroe and State of New York, have invented a new, original, and ornamental Design for a Shoe Tree, of which the following is a specification, reference being had to the accompanying drawing, forming part thereof, and in which:

Figure 1 is a plan view of a shoe tree showing my new design.

Figure 2 is a side elevation of the same.

Figure 3 is a bottom plan view of the shoe tree.

My design for shoe tree, as shown, is characterized by the convex formation of the top surface of the rear or heel portion of the shoe tree with the ornamental adjusting pin projecting thereabove adjacent the inner end thereof and the cord loop adjacent the outer end thereof, in combination with the configuration of the rear top of the forward portion of the shoe tree.

I claim:

The ornamental design for a shoe tree, as shown and described.

JAMES B. MUTCH.
